VENDING MACHINE ATTACHMENT

Carl R. Simpkins, Inglewood, Calif., and Bruno Radtke, Libertyville, Ill., assignors to The Exhibit Supply Company, Chicago, Ill., a corporation of Illinois

Application April 25, 1935, Serial No. 18,172

6 Claims. (Cl. 194—1)

This invention relates to a vending machine attachment.

It is an object of this invention to provide an improved vending machine attachment which is 5 relatively simple and inexpensive in construction and efficient in use.

Another object of the present invention is to provide an attachment for coin-controlled vending machines, particularly those of the so-called 10 "digger" or "crane" type, and which is so constructed that the coin control and associated vending mechanism can not be operated if the merchandise storage magazine embodied in the attachment is empty; or, in other words, unless 15 there is a quantity of the vendible commodity in the storage magazine.

Other objects will appear hereinafter.

The invention consists in the novel combination and arrangement of parts to be hereinafter 20 described and claimed.

The invention will be best understood by reference to the accompanying drawing, showing the preferred form of construction and in which:

Fig. 1 is a fragmentary vertical sectional view 25 of a vending machine showing a preferred form of the present invention associated therewith;

Fig. 2 is a vertical sectional view on line 2—2 in Fig. 1;

Fig. 3 is a vertical sectional detail view, on 30 line 3—3 in Fig. 1, showing the coin-controlled latching device embodied in the invention;

Fig. 4 is a view, on line 4—4 in Fig. 1, partly 35 in section and partly in bottom plan; and

Fig. 5 is a perspective detail view of a part of 40 the vending machine attachment.

The present invention is particularly adapted 45 to be associated with a coin-controlled vending machine of the so-called "crane" or "digger" type, and a portion of the cabinet of such a vending machine is shown in the drawing, is therein generally indicated at 10, and comprises a merchandise storage or display compartment 11 having a transparent front wall 12; said display compartment being adapted to contain a quantity of a vendible commodity 13 which might be, for example, candy or the like.

There is a tendency for candy or other edible, vendible commodities, upon standing in the display compartment 13, to spoil and become unfit 50 for use, and to overcome this objectionable feature the present invention provides an article storage hopper or magazine 14 which is provided with a flange 15 by means of which the hopper 14 is mounted upon a horizontal wall 16 of the cabinet 10.

The hopper 14 is provided with an open top 17 over which is arranged a closure 18. The hopper 14 is provided with converging sloping bottom walls 19 and below the point of convergence of these walls 19 the hopper 14 is provided with 5 a discharge spout or outlet 20 which is adapted to hold a predetermined measured quantity of a vendible commodity. Arranged below this discharge outlet or spout 20 is an inclined delivery or discharge chute 21 which opens, as at 22 (Fig. 10 1), exteriorly of the cabinet 10 through an opening provided in the front wall 23 thereof.

Slidably mounted above the discharge outlet 20 of the hopper 14 is a valve 24 which is provided with a discharge opening 25 and this slidable 15 valve 24 has a depending finger 26 to which is attached a resetting spring 27 by means of which the slide valve 24 is normally retracted into position (as in full lines, Fig. 1) to prevent communication between the hopper 14 and the discharge 20 outlet 20 of the same.

Pivotedly mounted in the cabinet 10, as at 43, below the discharge outlet 20 of the hopper 14 is a dispensing valve plate 28 which is adapted to hold a measured quantity of merchandise in 25 the outlet or chute 20 of the hopper. Attached to this dispensing valve or plate 28 are spaced arms 29 which are adapted to engage the depending arm 26 of the slidable valve 24.

The dispensing valve 28 has an arm 30 to which 30 is attached a spring 31, this spring 31 also being attached to a link 32 which is, in turn, pivotally mounted in the cabinet 10, as at 35; this member 32 having a pin and slot connection 33 with a disc 34 which is carried by a motor driven shaft 35 36 which is arranged within the cabinet 10. The dispensing valve 28 has a lateral extension or arm 42 with which the link 32 is engageable.

Mounted upon a horizontal shaft 37 which extends into the hopper 14, is a plate 38, and this 40 shaft 37 has an angled end portion 39 which is latchingly engageable in a notched edge portion 40 of the coin slide 41 which is slidably mounted in the front wall 23 of the cabinet 10.

Operation

45

A quantity of an edible or other vendible commodity of merchandise may be displayed in the display compartment 11, and another quantity of the same merchandise may be placed in the 50 hopper 14. At a certain time during the operation of the power driven shaft 36 and the disc 34 carried thereby, the pin 33 acts upon the link 32 to pivot the dispensing valve 28 from its normal or initial position (as in full line position 55

"A", Fig. 1), clockwise, into dotted line position "B"); this movement of the link 32 being transmitted to the valve 28 by the spring 31. During this movement the arms 29 of the dispensing valve 28 engage the depending arm 26 of the slide valve 24 and move the latter (left to right, Fig. 1), thereby registering the discharge aperture 25 in the slide valve 24 with the open lower end of the hopper 14, so as to discharge a predetermined or measured quantity of a vendible commodity from the hopper 14 into the spout 20 and onto the dispensing valve 28; whereupon, the valve 28 is reset into its initial position (position "A", Fig. 1) by the action of its resetting spring 31. At a subsequent stage in the operation of the motor driven shaft 36, disc 34 and link 32, the dispensing valve 28 is moved (counter-clockwise, Fig. 1, from position "B" to position "C"), thereby moving the valve 28 out from under the discharge chute 20 and thus permitting the measured quantity of merchandise contained in the chute 20 to be discharged from the chute 20 onto the inclined delivery chute 21 by which it is delivered exteriorly of the cabinet 25 to the purchaser; it being noted that this movement of the dispensing valve 28 (from position "A", Fig. 1 to position "C") is effected by engagement of the link 32 with the arm 42 of the valve 28. Subsequently the dispensing valve 28 is returned to its normal or initial position, as at "A", Fig. 1, by its resetting spring 31, and the slide valve 24 is reset into its initial position, as in full lines, Fig. 1, by means of its resetting spring 27.

35 The coin slide 41 may be operated, to effect the operation of the vending machine (which may be of the "crane" or "digger" type), as long as there are articles of merchandise in the hopper 14, since as long as there are any of such articles in the hopper 14, the same will gravitate down the inclined side walls 19 of the hopper 14 and will bear against the latch plate 38 and thereby cause the latter to act upon the shaft 37 to pivot the latching end portion 39 of the latter out of engagement with the notched portion 40 of the coin slide 41. However, as soon as the last of the vendible articles has been discharged from the hopper 14 into the measuring pocket 20, the latch plate 38, acting as a pendulum, returns by gravity to its initial position, as in full lines, Fig. 2, and in so doing rocks the shaft 37 into position to dispose the angled end portion 39 thereof in latching engagement with the notched portion 40 of the coin slide 41, thereby latching the coin slide 41 and associated vending mechanism (not shown) against operation until a further supply of vendible articles is placed in the hopper 14, whereupon the latch plate 38 is again moved, by the pressure of such articles, into a position to rock the shaft 37 so as to move the angled end portion 39 thereof out of latching engagement with the notched portion 40 of the coin slide 41.

65 In this manner the coin slide 41 and associated vending mechanism (not shown) are latched against operation if and when the hopper 14 becomes empty.

70 While only part of the operating mechanism of the vending machine is shown it is to be understood that the present invention is not limited to use with any specific type of vending machine but may be used with any type of vending machine in which the vending mechanism is actuated by a coin-controlled device. In the preferred 75 form of the invention shown, however, it is to

be understood that the coin slide 41 actuates the vending mechanism of a vending machine of the crane type and such machines include a motor driven shaft 36, the circuit to the motor which operates this shaft 36 being controlled, in a conventional manner, by the coin slide 41.

5 While we have illustrated and described the preferred form of construction for carrying our invention into effect, this is capable of variation and modification, without departing from the 10 spirit of the invention. We, therefore, do not wish to be limited to the precise details of construction set forth, but desire to avail ourselves of such variations and modifications as come within the scope of the appended claims.

15 Having thus described our invention, what we claim as new and desire to protect by Letters Patent is:

1. In a vending machine, a cabinet, an article storage magazine in said cabinet, a coin control 20 including a slide movably mounted in a wall of said cabinet and having a notched latch part, means for latching said coin slide against operation when said storage magazine is empty, said means comprising a member pivoted on an interior wall of said magazine and having a latch rod extended therefrom and movable therewith for normal latching engagement with the notch part of said slide and being movable out of latching engagement with the notched latch part of 25 the slide responsive to the pressure of articles against said pivotally mounted member in said magazine.

2. In a vending machine, an article storage magazine, a coin-operated control including a 35 reciprocal control member having means for engagement by a latch device, and latch means for said control member to prevent operation of the same when said magazine is empty, said means including a member pivotally mounted on 40 an interior wall of said magazine and having a latch rod extended therefrom and movable therewith for latching engagement with the said latch-receiving means of the reciprocal control member, the said pivotally mounted member being normally adapted to move by gravity in a manner to move said latch rod into latching engagement with the control member and being further adapted by the pressure of articles thereagainst in said magazine to move 50 said latch rod out of latching engagement with the control member.

3. A vending machine having an article storage magazine and a coin-operated control including a reciprocal control member having a 55 latching notch and latching mechanism for preventing the operation of said coin-operated control when said magazine is empty, said mechanism comprising a plate-like member pivotally mounted on a wall of said magazine and having 60 a portion exposed to contact with articles therein, said pivotally mounted member having a latching member extended therefrom and movable into and out of latching engagement with the latching notch of said reciprocal member, the latter being normally positioned by gravity in a manner to move said latching member into latching position and being movable by the pressure of articles in said magazine to move said 65 latching member out of latching engagement with the latching notch of said reciprocal member.

4. In a vending machine, a cabinet, an article storage magazine in the cabinet, a coin slide 75

having a latch-receiving notch movably mounted in a wall of the cabinet and means for latching the said slide against operation when the article storage magazine is empty, said means comprising a plate-like member supported for pivotal movement on a wall of said magazine and having a portion exposed to contact with articles in the magazine, the pressure of such articles against said plate-like member moving 5 the same in a direction outwardly of the magazine, a latch rod operatively connected to said plate-like member and having a portion movable into and out of latching engagement with the notch part of said slide by movement of 10 the plate-like member, the latter being positionable by gravity when there are no articles in the magazine to move said latch rod into latching engagement with said slide, and being movable by the pressure of articles thereagainst 15 to move said latch rod out of latching engagement with the slide.

5. In a vending machine, a storage hopper for vendible merchandise and a coin controlled member for releasing merchandise and including 20 a coin slide having a latching notch, control means comprising a control member supported for pivotal movement in a direction into and out of said hopper and having a portion exposed to contact with merchandise in the hopper, a latch rod supported for movement into and out of latching engagement with the notched portion of said coin slide and adapted to prevent movement of the latter when the said hopper is

empty, said control member and said latch rod being operatively connected such that said rod is normally moved by said control member into latching engagement with the slide when said hopper is empty and there are no articles in 5 contact with the control member, and such that the said latch rod will be moved out of latching engagement with the slide by the pressure of merchandise against said control member.

6. A vending machine including a storage 10 hopper for merchandise articles, a coin-operated control including a frame member and a control member manually movable therein, the said frame and movable control having registered 15 latch notches adapted to receive a latch member to prevent movement of the movable control member, and latch means including a pivotally mounted member on a wall of said hopper and having a portion exposed for engagement with articles therein, the said pivoted member 20 having a latch rod operatively connected thereto and being disposed in a normal position to hold said latch rod in latching position relative to the latch-receiving notches in said frame 25 and control members, the said pivotally mounted member being movable by engagement with merchandise articles in said hopper to position said latch rod out of latching engagement with the latching notches in said frame and control members. 30
